UNITED STATES PATENT OFFICE.

RICHARD A. GREENE, OF BROOKLYN, NEW YORK, ASSIGNOR TO JABEZ BURNS & SONS,
A CORPORATION OF NEW YORK.

NUT-MILL.

1,290,975.

Specification of Letters Patent. Patented Jan. 14, 1919.

Application filed December 22, 1916. Serial No. 138,370.

To all whom it may concern:

Be it known that I, RICHARD A. GREENE, a citizen of the United States, residing at Brooklyn, in the county of Kings and State 5 of New York, have invented certain new and useful Improvements in Nut-Mills, of which the following is a specification.

This invention relates to nut mills, and has particular reference to improvements in mills of the worm feed type commonly employed for grinding peanuts and similar materials. The object of this invention is to provide improvements in the construction of such mills, and also to provide in combination with the feeding mechanism means for automatically supplying a proportion of seasoning material, such for example, as salt.

According to this invention, a nut mill of improved construction permitting ready dis- 20 assembling for cleaning, etc., is provided in combination with power operated means for automatically supplying salt or other seasoning material, so that the seasoning mate- 25 rial will be thoroughly incorporated with the nuts at the time they are ground.

In the accompanying drawings, Figure 1 is an elevation partly in section, of the im- 30 proved machine;

Fig. 2 is an end elevation seen from the 35 left of Fig. 1, and Fig. 3 is a plan view;

Fig. 4 is a detail of the salt feeding mech- 40 anism, and

Fig. 5 is a section on the line 5—5 of 45 Fig. 4.

1 represents a base carrying bearings 2—2 in which is journaled the sleeve 11 carrying shaft 3 having feeding worm 4, and the grinding cone 5, removably fastened thereto by the scraping nut 56. The grinding cone

5 fits within the stationary cone 6 mounted in the base, and 7 represents a cooling water jacket. The nuts are fed by the worm 4 and forced out between the grinding cone 5 and the stationary cone 6 into a removable casing

8 having a discharge spout 9. The sleeve 11 is separably fastened to shaft 3 by pin 12 passing through collar 13 at one end, so that the sleeve 11 turns with the shaft 3. By dis- 45 connecting the shaft from the pin, the shaft

3 carrying the movable cone 5 can be re- 50 moved end-wise when the case 8 is removed. This avoids disturbing the other driving parts of the machine, all of which are mount- ed on the sleeve 11.

55 16 is the end bearing for sleeve 11, and

loosely mounted on this sleeve is the driving pulley 17, which is connected by clutch 18 to a clutch hub 19, fastened to sleeve 11, by screw 20. The clutch 18 is operated by toggle links 21 carried by the clutch yoke 22 on 60 the hub 19. The clutch yoke 22 is connected to a ring 23 which latter is connected by side links 24 to the operating lever 25. The links 21 are adjustable by means of turn buckles 27. 28 is a ball thrust bearing between the 65 clutch and the bearing 16. Mounted on the sleeve 11 is a driving pulley 29 carrying a belt 30 which runs over a driving pulley 31 on shaft 32, which operates the salt shaking mechanism. The distance between the grind- 70 ing surfaces of grinding cone 5 and stationary cone 6 is adjusted by means of a lever 33 pivoted on the base 1 at 34 and engaging a collar 14, to operate against spring 26. By operating the hand wheel 35 on threaded 75 shaft 36 and having nuts 37 engaging lever 33 the entire sleeve 11, shaft 3 and grinder 5 can be shifted longitudinally. The lever also holds the spring under compression while the shaft is being removed and in- 80 serted.

The nuts are put into a hopper 38 and fall by gravity through the chute 39 to the inner or right-end of the worm 4. As seen in Fig. 1, the chute 39 is made of relatively light 85 material and fits over a flange 40 carried by the base, and opening through the casing directly to the worm. The hopper 38, in order to save space, is made round, and one corner of it is cut out in order to receive the 90 salt receptacle 41. As seen in Fig. 4, the salt receptacle comprises a generally rectangular box having an inclined shaking bottom 42 similar to a trough, and supported at an in- 95 clinied position so as to slide transversely on pins 43. 44 represents a gate at the lower end which is adjusted to vary the opening by means of a hand-lever 45 mounted on shaft 46, and connected with the gate 44 by an arm 47. The handle 45 moves over a 100 scale or index 49 so that the degree of open- ing of the gate can be determined by inspec- tion. The trough shaped bottom of the salt holder 41 is operated by an eccentric 50 on the shaft 32; the bottom 42 of the salt holder 105 is fastened to the yoke 48 which is engaged by the eccentric 50. 51 are flexible flaps which prevent the salt from working up and around the sides of the trough 42. From the lower end of trough 42, the salt falls into 110

a pocket 52 and then slides by gravity into the chute 39. The feed of the nuts is controlled by a sliding gate 54, which is set in the desired position by set screw 55.

- 5 The advantageous features of this machine reside in the facility with which the grinding cone 5 can be removed independently of the driving mechanism, simply by disconnecting the sleeve 11 from the shaft
- 10 3; the adjustability of the clutch; and the combination of the automatic salt feeding mechanism having its own means of adjustment. A further feature of advantage of this machine resides in its compactness and
- 15 15 in the arrangement of the parts, so that the operator can tell at a glance not only the proportion of salt which is being fed, but also the proportion of nuts. It will be seen that by this machine, a uniformly seasoned
- 20 20 product will be produced with any given adjustment, which, so far as I am aware, has not heretofore been accomplished in mills of this class. This invention is espe-

cially useful in the manufacture of so-called peanut and other nut butters, but is applicable to various other purposes without departure from the scope of the invention. The details of construction herein shown are also capable of various modifications and changes without departing from the scope 30 of the appended claim.

I claim:

A nut mill comprising a frame carrying a stationary and a movable grinder, a feed screw connected with the movable grinder, a 35 sleeve journaled in the frame and having a separable driving connection with said feed screw, means for driving the sleeve, means on the frame for longitudinally adjusting the sleeve with the feed screw and movable grinder, the feed screw and movable grinder being removable laterally of the stationary grinder upon being disconnected from the sleeve independently of the driving means and without affecting the adjustment.

RICHARD A. GREENE.
